BASE DETONATING FUSE

Lyle K. Liljegren, Alexandria, Va.

Application May 22, 1945, Serial No. 595,231

6 Claims. (Cl. 102—79)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to an improved construction of base detonating fuze for rotatably type projectiles which is armed during flight by centrifugal force and which is detonated upon impact of the projectile with a target by the inertia force thus produced.

More particularly, it is an aim of the invention to provide an improved construction of a projectile fuze including a novel construction of a plunger which is inertia actuated upon impact of the projectile with its target, and which supports a centrifugally actuated arming member which retains the fuze in a disarmed condition until after the fuze has left the bore of the weapon from which it is fired.

Still another aim of the invention is to provide a plunger having a novel means for supporting a primer which ignites an explosive train by means of which the bursting charge of the projectile is ultimately detonated.

Another object of the invention is to provide a fuze wherein the primer is carried by the plunger and movable relatively to a fixed striker or anvil.

A further object of the invention is to provide a fuze having novel means of simple construction to prevent casual release of detent members which function to retain the fuze in a safe or disarmed condition until the projectile, containing the fuze, is in flight.

Still another object of the invention is to provide a fuze having an indirect or circuitous flash passage between certain of the components of the powder train, which lead ultimately to the burster charge, for producing a delay firing of the booster charge after the fuze primer has been detonated.

Other objects and advantages of the invention will herein become more fully apparent from the following description of the drawings, which illustrates preferred embodiments thereof, and wherein:

Figure 1 is a longitudinal, substantially central sectional view of the preferred form of the fuze and taken substantially along a plane as indicated by the line 1—1 of Figure 2;

Figure 2 is a view similar to Figure 1 but partly in side elevation, taken substantially along a plane as indicated by the line 2—2 of Figure 1;

Figure 3 is a cross sectional view of the fuze taken substantially along a plane as indicated by the line 3—3 of Figure 1;

Figure 4 is a cross sectional view of the fuze

2

taken substantially along a plane as indicated by the line 4—4 of Figure 2;

Figure 5 is a view similar to Figure 1 of a modified form of the fuze; and

Figure 6 is a view similar to Figure 1 of another modified form of the fuze.

Referring more particularly to the drawings, wherein like reference characters designate like or corresponding parts throughout the several views, and referring particularly to Figures 1 to 4, 7 designates generally the improved fuze in its entirety and which includes a fuze housing 8 having a longitudinally extending chamber 9 which opens outwardly of the inner end 10 thereof. A sleeve 11 is mounted in the open end of the chamber 9 and is secured therein by any suitable means such as a press fitting. Sleeve 11 is provided with an internally threaded outwardly opening bore portion 12 and has at its inner end a restricted opening 13 which opens into the bore portion 12 and into the inner end of the chamber 9. A head 14 is provided with a restricted, externally threaded neck 15 which extends into and is in threaded engagement with the threaded bore 12. A plurality of sealing gaskets or rings 16 are clamped between the head 14 and the inner end of the fuze housing 8. An anvil or striker 17 is provided with a base which is clamped between the annular shoulder 18, formed by the opening 13, and the free end of the neck 15. The striker 17 is provided with a shank or stem 19 which extends axially through opening 13 and into the inner end of the chamber 9. The neck 15 is provided with a recess 20 containing a detonator 21 and the head 14 is recessed at 22 to receive a burster charge 23 which is retained within the recess 22 by a readily destructible closure 24. The neck 15 is provided with a flash passage 25 connecting the burster charge 23 to the detonator 21.

A plunger 26 is mounted to slidably engage the inner end of the chamber 9 and is disposed for sliding movement lengthwise thereof toward and away from the striker element 19. The end of the plunger 26, which faces the striker element 19, is provided with a recess 27 containing a primer 28 and a head 29 is anchored in the plunger 26 and is embedded in the primer 28, in alignment with striker element 19. As clearly illustrated in Figure 1, the recess 27 is of a sufficient size and is correctly located to receive the striker element 19 when the plunger 26 is moved forwardly or toward the striker element. Plunger 26 is provided with a plurality of longitudinally extending grooves 30 which extend from end to end

thereof and which open outwardly of the periphery.

A detent, designated generally 31, includes a base 32 which is disposed against the outer end of the plunger 26 and which is provided with a plurality of integral spring arms 33 which are normally disposed at acute angles to the base 32. One of the spring arms 33 extends lengthwise through each of the grooves 30. The spring arms 33 extend beyond the forward face of the plunger 26 and are provided with heads 34 which are fastened to the inner sides of the free ends of the arms 33 and which project inwardly therefrom. The heads 34 form centrifugal actuated weighted elements, for a purpose that will hereinafter be described. As best seen in Figure 1, the heads 34 are normally disposed between the surface 35 of the plunger 26 and the annular shoulder 18 to prevent the plunger 26 from moving toward the striker element 19. As seen in Figure 1, the surface 35 is inclined outwardly and downwardly to provide an engagement with the heads 34 which will resist outward movement of the heads 34 and which will prevent said heads from moving out of engagement with surface 35 except when swung in an arc having an axis approximately at the secured ends of the spring arms 33. Thus, the surface 35 functions to prevent casual displacement of the heads 34 and premature arming of the fuze 7. Between certain of the grooves 30, plunger 26 is provided with longitudinally extending recesses 36 which open outwardly of its forward face and in which are slidably mounted the inwardly opening cup-shaped plunger elements 37. Each of the recesses 36 contains an expansion coil spring 38 which extends into and bears against the plunger element 37 thereof for urging said plunger elements outwardly of the recesses 36 and against the shoulder 18, to retain the plunger 26 in its retracted position, as seen in Figures 1 and 2.

The striker or anvil 17, between its base and its striker element 19, is provided with a tapered neck portion containing a plurality of downwardly converging flash passages 39 which communicate with the opening 13 at their rear ends and with the recess 20, containing the detonator 21, at their forward ends.

Assuming the fuze 7 to be mounted in the base of a projectile, not shown, the fuze parts will be in their safe or disarmed positions, illustrated in Figures 1 and 2, prior to the time that the projectile is fired from a weapon and while it is moving through the weapon barrel and for a short time thereafter. While thus disposed, the fuze 7 is safe and therefore renders the projectile, in which it is contained, bore safe. No manual operation is necessary to arm or prepare the fuze for arming prior to the fuze being fired with its projectile, so that there is no danger of duds resulting due to the oversight of a member of the gun crew failing to arm or set the fuze for arming, prior to firing of the projectile. After the projectile, containing the fuze 7, has been fired and when it has reached substantially its maximum speed of rotation, the weighted heads 34 will be swung outwardly by centrifugal force against the spring action of the arms 33 so that said heads will be in alignment with the grooves 30, which are wider than the width or diameter of the heads 34, as seen in Figure 2. With the heads 34, thus disposed, the fuze 7 is armed and ready to function and the plunger 26 is held in its retracted position by the spring biased plunger elements 37 so that deceleration of the projectile will not de-

tonate the fuze. Upon impact of the projectile containing the fuze 7 with a target, the plunger 26 will be driven forward by inertia against the resistance of the springs 38 and in so moving, the heads 34 will be received in the grooves 30 and the striker element 19 will be received in the recess 21. Striker element 19 will thus be caused to strike the primer 28 which will be compressed thereby between the striker element 19 and the head 29 to detonate primer 28. The flash from primer 28 will pass through opening 13 and the converging flash passages 39 to the detonator 21. The flash from the ignited detonator 21 will detonate the booster charge 23 which will in turn detonate the booster charge of the projectile, not shown. The converging shape of the flash passages 39 produce a slight delay in conveying the flash from the primer 28 to the detonator 21, which is advantageous in order that the projectile can embed itself in its target before its burster charge is detonated.

Figure 5 illustrates a slightly modified form of fuze, designated generally 40, having a housing 8, corresponding to the housing of the fuze 7 and containing a cavity 9 in the open end of which is mounted a sleeve 41. Sleeve 41 is provided with a recess including a forwardly opening inwardly threaded portion 42 and a rear portion 43 containing a primer holder 44 in which is mounted a primer 45. The inner end of the sleeve 41 is provided with a restricted opening 46 which communicates with the primer 45 and which forms an annular shoulder 47, surrounding the opening 46. A head 48 is provided with a restricted threaded neck 49 which extends into and threadedly engages the threaded portion 42. Sleeve 41 may be secured in the chamber 9 in the same manner as the sleeve 11, and the joint between the housing 8 and the head 48 is sealed by gaskets 16, as in the fuze 7. The neck 49 is provided with an enlarged recess 50 at its rear end containing a detonating charge 51 and a more restricted recess 52 containing a second detonating charge 53. The head 48 has a recess 54 containing a booster charge 55, which is separated from the detonator 53 by a readily destructible partition 56. The booster charge 55 is contained in the recess 54 by a readily frangible closure 57. The holder 44 and a portion of the detonator 51 are provided with 50 communicating bores forming a flash passage 58 between the primer 45 and the initial detonator 51.

The inner end of the chamber 9 contains a plunger 59 which is disposed for sliding movement lengthwise of the housing 8 and which is provided with a plurality of longitudinally extending grooves 60 which open radially of the plunger 59 and which extend the length thereof, and the beds of which grooves 60 converge toward the forward end of the plunger 59. The plunger 59 is provided with a detent 31, corresponding in construction and operation to the detent of the fuze 7 and differing therefrom only in slight variations of size to adapt it to plunger 59. The plunger 59 is provided with a forwardly projecting striker 61 which is axially disposed and aligned with the opening 46 and which is located between the weighted heads 34. The weighted heads 34 normally bear against the outwardly and downwardly inclined surface 62 of the plunger 59 and are disposed to engage the shoulder 47 to prevent the striker 61 from moving into the opening 46, until the heads 34 are moved outwardly by centrifugal force to arm the fuze 40. Plunger 59 is provided with springs 38 and plungers 37, one of a plurality of sets of which is shown

in Figure 5, for holding the plunger 59 in a retracted position, after the detent 31 has moved to its fuze arming position.

From the foregoing, it will be apparent that the fuze 40 is armed in the same manner as the fuze 7, during flight of the projectile in which it is contained, and upon impact of the projectile with a target, plunger 59 is moved forward by inertia with its groove 60 receiving the heads 34, thereby causing its striker or firing pin 61 to engage or detonate the primer 45. The flash from the primer 45 passes through flash passage 58 to detonate the initial detonator 51, the flash from which ignites detonator 53. Detonator 53 in turn ignites the booster charge 55 which in turn sets off the burster charge of the projectile, containing the fuze 40.

In Figure 6 another variation of the fuze, designated generally 63, is illustrated, having a slightly modified form of housing 64 which is reduced in length and which contains a shortened chamber 65. A coupling member 66 is provided with a neck 66' which extends into the forward end of the chamber 65 and which is suitably secured to the housing 64. Coupling member 66 is provided with a forwardly opening recess 67 containing a sleeve 68 having a forwardly opening internally threaded cavity 69. A head 70 is provided with a threaded neck 71 which engages the cavity 69 and which is recessed to contain a detonator 72. The head 70 is provided with a recess 73 containing a booster charge 74. Said recess 73 is closed by a frangible closure 75. The sleeve 68 is provided with a very restricted passage 76 which connects the chamber 67 with the detonator 72, and the neck 67 is provided with flash passages 77 which communicate with the rear end of the chamber 65 and the chamber 67. Neck 66' is provided with an integral anvil or striker 78 which projects axially into the chamber 65.

Chamber 65 slidably mounts a plunger 79 having a centrally disposed forwardly opening recess 80 into which the rear end of the striker 78 extends and in the rear end of which is contained a primer 81, which is spaced from the striker 78. Plunger 79 is provided with longitudinally extending grooves 82 for receiving the spring arms of a detent 31 which is carried by the plunger 79, and which corresponds to the detents of the fuses 7 and 40.

The fuze 63 is armed during flight in the same manner as the fuses 7 and 40, and after arming, the plunger 79 is held in a retracted position by plungers 37 and springs 38, one of which plungers 37 is shown in Figure 6. Upon impact of the projectile, containing the fuze 63, plunger 79 is driven forwardly by inertia causing the primer 81 to strike the anvil 78 and be detonated thereby. The flash from the primer 81 is conveyed through passages 77, the inner part of cavity 67 and through the passage 76 to the detonator 72. The flash from the ignited detonator 72 is conveyed by means of a passage 82, in the neck 71, to the booster charge 74 which upon being detonated sets off the projectile charge, not shown.

Obviously, various other modifications and changes in the construction and arrangement of the parts forming the fuze are likewise contemplated and may be resorted to without departing from the spirit and scope of the invention, as hereinafter defined by the appended claims.

I claim:

1. A base detonating centrifugally armed projectile fuze comprising a housing having a forwardly opening chamber, an internally threaded sleeve disposed in the forward end of the chamber, a head having a threaded neck extending into and threadedly engaging the sleeve, said neck having a chamber containing a detonator, an anvil disposed in the sleeve and extending into the inner end of the housing chamber, said head being recessed to contain a booster, a flash passage connecting the booster and detonator, a plunger slidably mounted in the outer end of the housing chamber for movement toward the anvil, said plunger having an inwardly opening recess to receive the anvil when the plunger is moved forward by inertia, a primer in said plunger recess to be engaged by the anvil, a flash passage in the anvil for conveying the primer flash to the detonator, and a centrifugally actuated detent carried by the plunger and normally disposed between portions of the plunger and sleeve to retain the fuze in a safe or disarmed condition, said detent being movable to an inoperative position, upon rotation, for arming the fuze.
2. A fuze as in claim 1, said plunger having longitudinally disposed grooves, said detent including spring arms extending through said grooves and therebeyond, and heads mounted on the free ends of the arms and extending inwardly therefrom and being disposed between surfaces of the plunger and sleeve, said heads being retractable, by centrifugal force, into alignment with the grooves to arm the fuze.
3. A fuze as in claim 1, the flash passage, formed in the anvil, being disposed to provide an indirect passage between the primer and detonate to produce a delay action in the ignition of the detonator.
4. A fuze as in claim 1, and a head carried by the plunger and embedded in the primer, said primer head being in alignment with the anvil.
5. A fuze as in claim 1, and spring pressed means slidably mounted in the plunger and extending therefrom and engaging the sleeve for yieldably retaining the plunger in a retracted position.
6. A fuze as in claim 1, the surface of the plunger, disposed to engage the detent to prevent detonation of the fuze, being inclined outwardly and downwardly to resist casual movement of the detent to a fuze arming position.

LYLE K. LILJEGREN.
